Inventor.

William M. Scott

UNITED STATES PATENT OFFICE.

WILLIAM M. SCOTT, OF BIRMINGHAM, GREAT BRITAIN.

IMPROVEMENT IN MEANS OF ATTACHING THE FORE END TO GUN-BARRELS.

Specification forming part of Letters Patent No. **157,699**, dated December 15, 1874; application filed July 19, 1873.

To all whom it may concern:

Be it known that I, WILLIAM M. SCOTT, of the city of Birmingham, Kingdom of Great Britain, have invented a new and useful Improvement in Attaching the "Fore End" of a Gun-Stock to the Barrels; and I do hereby declare that the following is a full, clear, and exact description thereof, reference being had to the accompanying drawings, making part of this specification, in which—

Figure 1 represents a central longitudinal section of a portion of a double-barrel gun through the ribs, to which the barrels are secured, having my improved spring-catch applied thereto. Fig. 2 is a similar section to Fig. 1, representing a modification of the spring-fastening. Fig. 3 represents a plan of the inner face of the fore end of a gun-stock prepared to receive my improved fastening.

Like letters indicate corresponding parts in all of the figures.

My invention relates to securing the fore end of a gun-stock to the barrels, and releasing the same therefrom, by means of a self-acting spring-catch and sliding thumb-bolt, constructed and arranged substantially as herein described.

To the inner surface D of the fore end of a gun-stock, B, is fitted a metal strap, E, and secured thereto by means of screws *a*. Upon this strap E are mounted the several parts constituting the spring-catch proper, and by which the fore end of the stock is held firmly in place against the lower surface of the gun-barrels. Projecting from the lower side of the lower rib C is the usual lug F, in the edge of which a notch, *c*, is formed to receive the corresponding-shaped face of the catch *o*. This catch *o* is pivoted at *r* to the metal strap E, and is forced into the notch *c* by a spring, *s*, which is also secured to the strap E.

By this arrangement of spring-catch *o* and notched lug F, it will readily be seen that the fore end of the gun-stock is forced against the lower sides of the barrels, and retained there in consequence of the spring-catch *o* operating in the arc of a circle, the spring *s* forcing the

face of the catch *o* eccentrically or downward against the notch *c*, as represented.

To relieve the face of the catch *o* from the notch *c* in the edge of the lug F, so as to remove the fore end of the stock from the barrels, a sliding spring thumb-bolt, *G*, is arranged and secured to the fore end of the stock B, the end *r'* of the bolt bearing against the lower side of the stem *u* of the catch. This spring thumb-bolt is mounted in a guide, *w*, which guide is secured to the fore end of the stock by a screw, *v*.

Thus by simply placing the fore end of the stock B in position, and slightly pressing it toward the barrels, the spring-catch will take into the notched lug, and firmly retain the fore end of the stock against the lower surfaces of the barrels, because of the spring-catch bearing constantly against the lower side of the notch in the lug F.

In Fig. 2 the spring *s* forms the catch, and takes directly into the notch in the edge of the lug F, the end *n* of the sliding spring thumb-bolt acting as a wedge to release the spring in removing the gun-stock.

It is evident to those skilled in the art that many modifications of my invention may be produced, differing only in form, and without departing from what is here claimed; and I desire to be understood as not confining myself to the precise arrangement herein shown and described, but to embrace its mechanical equivalent.

Having thus fully described my improvement in a self-acting spring-catch for securing the fore end of a gun-stock to the barrels, what I claim therein as new, and desire to secure by Letters Patent, is—

The combination, with the fore end of a gun-stock, of a spring-catch and sliding thumb-bolt, for connecting the fore end with the barrel, the combination being and operating substantially as described.

WILLIAM M. SCOTT.
